United States Patent Office

Des. 190,313
Patented May 9, 1961

190,313

SPRINKLER

Russell B. Nelson, Peoria, and Robert K. Unter, Roscoe, Ill., assignors to L. R. Nelson Mfg. Co., Inc., Peoria,
Ill., a corporation of Illinois

Filed July 15, 1960, Ser. No. 61,377

Term of patent 14 years

(Cl. D91—1)

Fig. 1

The dominant features of our new design are shown in solid lines.

We claim:

The ornamental design for a sprinkler, as shown and described.
